UNITED STATES PATENT OFFICE.

WILLIAM C. RENTZ, OF ATLANTA, GEORGIA.

SPARK PLUG.

Application filed June 26, 1924. Serial No. 722,510.

To all whom it may concern:

Be it known that I, WILLIAM C. RENTZ, a citizen of the United States, residing at Atlanta, in the county of Fulton and State 5 of Georgia, have invented new and useful Improvements in Spark Plugs, of which the following is a specification.

This invention relates to improvements in spark plugs and has for an object the provision of a plug which includes a spark gap, whereby the spark across the power and ground electrodes will be intensified.

To this end, the invention aims to provide a plug which includes an intensifying 10 spark gap constructed so that the degree of the gap will be constantly maintained, so as to insure proper operation of the plug.

Another object of the invention is the provision of a spark plug of the above character which is simple in construction, readily assembled and which may be sold at a moderate cost.

With the above and other objects in view, the invention further includes the following 25 novel features and details of construction, to be hereinafter more fully described, illustrated in the accompanying drawings and pointed out in the appended claims.

In the drawings:

30 Figure 1 is an elevation of a spark plug constructed in accordance with the invention.

Figure 2 is a sectional view of the same.

Figure 3 is a detail sectional view of the 35 cap.

Figure 4 is a sectional view of the disk.

Figure 5 is a detail view of the power electrode.

Figure 6 is a bottom plan view of the cap.

40 Referring to the drawings in detail wherein like characters of reference denote corresponding parts, the reference character 10 indicates the core of the plug which is formed of suitable insulating material 45 and which is mounted within a shell 11, the latter carrying the usual ground electrode 12.

The core 10 is provided with a centrally 50 arranged longitudinally disposed opening 13 which is reduced in diameter for a portion of its length as indicated at 14, so as to provide a shoulder 15. Located within the opening 13 is the threaded portion 16 of a power electrode, the latter having a 55 threaded engagement with a sleeve 17 and

being provided with a reduced portion 18 which extends through the reduced portion 14 of the core opening. The portion 18 of the power electrode is surrounded by a sleeve 19.

The outer end of the power electrode is spaced from the adjacent end of the core and a disk 20 extends over this end of the core and closes the opening 13. This disk is held in place by means of a cap 21 whose edge is bent over a shoulder 22 provided upon the outer periphery of the core. The cap 20 carries a threaded stem 23 upon which is mounted a binding nut 24, so as to provide a binding post for engagement 70 with the usual conductor wire.

The disk 20 is of novel construction in that it is formed of Monel metal, or other suitable heat resisting metal so that the constant firing of the plug will not burn 75 away the disk and thus increase the distance between said disk and the adjacent end of the power electrode and destroy the efficiency of the spark gap thus provided. Further, the disk 20 is provided with a 80 centrally offset portion 25 which reinforces and strengthens the disk at this point, so that the portion of the disk subjected to the greatest heat will be reinforced and strengthened and tendency to warp will be 85 prevented with the result that the proper degree of spark gap will be constantly maintained.

The invention is susceptible of various changes in its form, proportions and minor 90 details of construction, and the right is herein reserved to make such changes as properly fall within the scope of the appended claims.

Having described the invention what is 95 claimed is:

1. In a spark plug, a shell, an insulating core within the shell, said core having an opening extending longitudinally therethrough, a power electrode within the core, the outer end of said electrode being spaced from the adjacent end of the core, a metal disk extending over and engaging the end of the core, a cap positioned over the end of the core and engaging the disk and an offset portion extending from the disk into and closing the adjacent end of the core opening and spaced from the adjacent end of the power electrode to provide a spark gap.

2. In a spark plug, a shell, an insulating core within the shell, said core having an opening extending longitudinally therethrough, a power electrode within the core,
5 the outer end of said electrode being spaced from the adjacent end of the core, a metal disk extending over the end of the core, a

centrally located offset portion extending into the core opening and spaced from the power electrode to provide a spark gap and 10 means for securing the disk in position.

In testimony whereof I affix my signature.

WILLIAM C. RENTZ.
